(57) **CLAIM**

The ornamental design for a swimmer starting platform, as
shown and described.

DESCRIPTION

FIG. 1 is an isometric view of a front, top, and left side of
an ornamental design for a swimmer starting platform;
FIG. 2 is a front elevational view of the swimmer starting
platform of FIG. 1;
FIG. 3 is a left side elevational view of the swimmer starting
platform of FIG. 1;
FIG. 4 is a rear elevational view of the swimmer starting
platform of FIG. 1;
FIG. 5 is a right side elevational view of the swimmer
starting platform of FIG. 1;
FIG. 6 is a top plan view of the swimmer starting platform
of FIG. 1;
FIG. 7 is a bottom plan view of the swimmer starting
platform of FIG. 1;
FIG. 8 is an isometric view of a rear, bottom, and left side
of the swimmer starting platform of FIG. 1;
FIG. 9 is an isometric view of a front, top, and left side of
another embodiment of an ornamental design for a swimmer
starting platform;
FIG. 10 is a front elevational view of the swimmer starting
platform of FIG. 9;
FIG. 11 is a left side elevational view of the swimmer
starting platform of FIG. 9;
FIG. 12 is a rear elevational view of the swimmer starting
platform of FIG. 9;
FIG. 13 is a right side elevational view of the swimmer
starting platform of FIG. 9;
FIG. 14 is a top plan view of the swimmer starting platform
of FIG. 9;

(Continued)

FIG. 15 is a bottom plan view of the swimmer starting platform of FIG. 9; and,

FIG. 16 is an isometric view of a rear, bottom, and left side of the swimmer starting platform of FIG. 9.

The broken lines are included for the purpose of illustrating environmental structure and form no part of the claimed design.
